(57) **CLAIM**

The ornamental design for an extendable desktop with sliding cover for bathtub and jacuzzi, as shown and described.

DESCRIPTION

1. Extendable desktop with sliding cover for bathtub and jacuzzi

1.1 : Perspective

1.2 : Perspective

1.3 : Front

1.4 : Back

1.5 : Left

1.6 : Right

1.7 : Top

1.8 : Bottom

1.9 : Bottom view with a sliding cover partially retracted

1.10 : Bottom view with a sliding cover fully retracted

The claimed design is used for installation on bathtubs and jacuzzis; it serves for covering the user's body when bathing in water or steam; it can also serve for covering the whole bathtub water or steam inside, keeping the temperature and humidity when connecting it with other covers (not shown in figures).
